STUART PARMELEE MILLER, OF TENAFLY, NEW JERSEY, ASSIGNOR TO THE BARRETT COMPANY, OF NEW YORK, N. Y., A CORPORATION OF NEW JERSEY

APPARATUS FOR THE PRODUCTION AND DISTILLATION OF TAR

Application filed March 5, 1927. Serial No. 172,962.

This invention relates to improvements in apparatus for the distillation of tars, and particularly to apparatus adapted to utilize the heat available in the gases produced in 5 coal-carbonization plants such as coke ovens to distill tar and to produce therefrom oils and pitches. The invention will be described especially with reference to its application to coke ovens.

10 In the ordinary operation of by-product coke ovens, the gases produced by the cooking operation pass from the individual ovens through uptake pipes and goose-necks to a collector main common to the ovens of the 15 battery. The gases, commonly known as "foul" gases, leave the ovens at high temperature, e. g., 600° to 700° C. or higher and carry a considerable proportion of tar and oil constituents. Ordinarily the gases are 20 cooled as rapidly as possible to relatively low temperatures, e. g., 100°-125° C., by the application of the sprays of ammonia liquor, or ammonia liquor and tar, in the goose-necks and collector main. The rapid cooling causes 25 considerable separation of tar containing the heavier oils in the collector main. Further cooling is effected in the cross-over main which connects the collector main to the condensing system and an additional quantity 30 of tar carrying both heavier and lighter oils is thus separated. Light tar or tarry oil is also collected from the condensers or coolers. The collected tar is ordinarily shipped from the coke-oven plant to a tar-distillation plant 35 for distillation and separation of the oils and the production of pitches of varying qualities. Handling losses, freight charges and distillation costs, including fuel and capital 40 and maintenance expenses for the special equipment required for distillation, add to the cost of production of the products of the distillation.

It is the object of the present invention to 45 provide apparatus which permits the distillation of tar at a coke-oven plant, the utilization of the heat of the coke-oven gases for that purpose, and particularly the production by such distillation of an increased quantity 50 of oils together with pitches having the vari-

ous qualities and characteristics required by the trade.

The apparatus of the present invention provides for utilizing the heat of the coke-oven gases as they come from the coke ovens 55 to distill tar and to separate vaporizable oils therefrom by spraying or otherwise bringing the tar into intimate contact with the hot coke-oven gases at a temperature sufficiently high to accomplish the desired distillation. 60 The amount of heat available in the hot coke-oven gases from a battery of coke ovens is, however, many times that required for distillation of the tar produced by such a battery, and the present invention is directed 65 more particularly to the utilization of so much of the heat as is required for the distillation of the tar produced by the battery, or such additional tar as may be available for distillation. The battery may be operated consequently in the usual manner and without substantial modification of the equipment ordinarily provided except insofar as provision is made for the distillation of the 70 tar in the manner hereinafter described and the utilization of a portion of the hot coke-oven gases for that purpose. 75

The battery may be provided with the usual uptake pipes and collector main or mains in which the hot coke-oven gases are 80 subjected to sprays of ammonia liquor, or ammonia liquor and tar, to rapidly cool the gases and thus throw down a considerable portion of the tar and heavier oils in the collector main. The remaining gases may be 85 further cooled in the cross-over main with resulting separation of an additional quantity of tar and oils after which the gases may be passed through the usual condensers to remove heavier and lighter tarry oils therefrom. The gases thus purified can then be 90 treated in the usual manner. The ammonia liquor can be separated from the tar and oils and returned to the collector main or utilized otherwise for the recovery of ammonia. The 95 foregoing involves merely the customary operation of a coke-oven battery. The tar and tarry oils recovered as described are crude products such as are usually mixed and shipped to the tar distillation plant. 100

In the apparatus of the present invention these crude tar products are subjected to distillation at the coke-oven battery by utilizing a portion of the heat of the coke-oven gases. This can be accomplished advantageously by providing a separate collector main which may be connected to one or more of the ovens of the battery so that the hot coke-oven gases from these ovens may be directed into intimate contact with the tar and oil to be distilled. The separate collector main can be disposed above, below or alongside of the ordinary collector main, but it may be placed advantageously at the rear of the battery and be connected to the selected ovens thereof by separate uptake pipes and goose-necks. The same ovens can be connected also to the usual collector main and valves can be provided to permit the direction of the gases from the ovens as desired into either of the collector mains.

The desired distillation of the tar and oil can be accomplished in a variety of ways involving the intimate contact of the gases therewith; for example, by spraying the tar or oil into the goose-necks leading to the separate collector main and into the separate collector main. Because of the high temperature of the gases, such intimate contact results in effective distillation and consequent separation of the volatile constituents of the tar or oil and the production of pitches or residues of varying consistency, depending upon the regulation of the operation with respect to the quantity of tar or oil and gases employed and the time during which they remain in contact.

The distillation can be promoted by mechanical agitation of the tar or oil in the separate collector main as, for example, by the provision of a shaft or shafts extending through the collector main and having paddles or other agitating means thereon so that as the shafts are rotated the tar or oil is thrown upwardly into the stream of gases and intimately mingled therewith. Agitation can also be accomplished by the introduction of compressed gases such as fuel gases, coke-oven gases, or steam into the tar or oil in the collector main so as to throw the tar or oil into the stream of gases. McDaniel ejectors supplied with such gases under pressure can be utilized thus to cause an intimate mingling of the tar or oil in finely divided form with the hot coke-oven gases.

Owing to the effective distillation of the tar or oil in the collector main pitch is produced and there is a tendency for hard pitch to accumulate on the walls of the collector main. To avoid such accumulation of hard pitch it is advantageous to flush all the collector main surfaces with an excess of hot tar or oil or pitch which may be introduced through the spray nozzles or through the end of the collector main. The tar or pitch re-

sulting from the distillation may be withdrawn either continuously or intermittently from the collector main and all or a portion thereof can be recirculated for further distillation and for the purpose of maintaining a sufficient body of tar or pitch in the main. 70

Since hard pitch is soluble in the hot tar or oil which is sprayed into the collector main or thrown into the gas stream so that the walls of the collector main are washed constantly with hot tar or oil, accumulations of hard pitch therein will be avoided and the collector main can be operated, if desired, continuously for the purpose of producing distillates from the tar and oils produced by the entire battery of coke ovens. 75 80

Although indiscriminate cooling of the gases in the short collector main is to be avoided since the primary purpose is to utilize the heat for the distillation of tar and oil, it may be desirable to introduce regulated amounts of water or ammonia liquor with the tar or oil which is sprayed into the short collector main to cool the gases to a predetermined and regulated extent. The regulation of the cooling effect can be accomplished readily with water because of the higher specific and latent heats of the water and its lower boiling point as compared with tar and oils. It is possible, therefore, to use water or ammonia liquor in addition to the tar or oil in the proportion required to remove all heat except that needed for the distillation of the tar or oil. When harder pitches are desired less water can be added or none at all and proportionately more tar or oil will be passed through the main. Cooling of the gases to some extent can be accomplished also by the addition thereto of cold gases such as fuel gas, cooled coke-oven gas, etc. 90 95 100 105

As an example of the operation, a plant comprising a single battery may produce tar and oils in the ordinary manner and the tar or oil or both so produced can be distilled with the heat provided in the gases from one or more ovens. Moreover, the tar produced by one or more batteries can be accumulated and it can be distilled from time to time in the separate collector main by utilizing the heat from the coke-oven gases supplied to that main. The operation is flexible inasmuch as the gases may be diverted at will from the separate collector main to the ordinary collector main when there is no tar to be distilled or when for any reason it is not desirable to carry on distillation in the short collector main. 110 115 120

While the invention is designed primarily to distill the tar produced at a coke-oven plant by utilizing some of the hot coke-oven gases from that plant, it is also possible to distill tar from other sources in the separate collector main. The tar distilled may contain all or practically all of the condensable 125 130

oils or it may be a heavy tar containing only part of the oils or mixtures of such tars. Heavy tar, light tar, or heavy or light tar constituents may be distilled for the purpose of separating distillate oils therefrom.

5 Other tar such as gas-house tar, vertical retort tar, or water-gas tar, etc., can also be distilled. Where blended or composite pitches are desired or composite or blended 70 distillates, two or more different kinds of tar 10 can be distilled separately at the coke-oven plant or they can be admixed in suitable proportions and can be distilled together giving directly a composite pitch product. For example, horizontal gas-retort tar with high 75 free carbon content can be admixed with coke-oven tar and the mixture can be distilled to give a composite pitch higher in free carbon than the pitch from the coke-oven tar and to 80 15 give a composite oil distillate.

20 Tar as commonly produced and collected at coke-oven plants contains more or less water or ammonia liquor admixed therewith. Such tar can be employed directly and de- 25 hydrated as well as distilled or it can be partially or completely dehydrated before subjecting it to distillation. The tar can also be preheated in any suitable manner to reduce it to a thinly fluid state which will fa- 30 cilitate the spraying of the tar into the collector main and ensure intimate contact there- 35 of with the hot coke-oven gases. The amount of heat contained in the hot coke-oven gases is, however, so great that effective dehydra- 40 tion as well as distillation can be accom- plished readily.

45 In carrying out the process the tar may be brought into contact with the hot gases only once or it may be recirculated and brought 50 again into contact with the hot gases to accom- plish a further distillation and the produc- 55 tion of harder pitches or even pitches of modified character such as those having in- creased free carbon content. This further 60 distillation may take place by recirculating the tar or pitch through the same collector 65 main or through another or other systems as, for example, successively through a series of 70 separate collector mains. By providing sep- 75 arate collector mains, each connected to a se- 80 ries of ovens, it is possible to produce distil- 85 lates and pitches of different characteristics simultaneously and by operating separate condensing systems with such separate distil- 90 lation systems, condensed products having 95 different properties can be produced simulta- 100 neously. By regulation of the spraying or agita- 105 tion of the tar and by redistillation when necessary, it is possible to regulate the 110 hardness of the pitches produced and to pro- 115 duce softer or harder pitches as desired.

120 The distillation of tar and oil may be regu- 125 lated not only for the production of desired distillate oils therefrom but also the produc- 130 tion of pitches of varying properties and

characteristics. By limiting the time or in- 135 timacy of contact or both of the tar or oil with hot gases, the temperature to which the tar is preheated and the temperature to which the tar is raised during distillation, pitches of 140 low carbon content and oils having definite characteristics can be produced as herein- 145 after described. When, however, the pitch first produced is recirculated its temperature 150 will be further raised and the temperature 155 can be increased to such an extent that more or less decomposition will take place with re- 160 sulting formation of free carbon, thus in- 165 creasing the free carbon content of the pitch. It is thus possible, by recirculation of the 170 pitch and by regulating the spraying or agi- 175 tation in the collector main so that the pitch is kept in contact with the hot gases for a 180 sufficient time to raise its temperature to the 185 decomposition temperature, to decompose or 190 crack greater or less amount of the pitch and/or oil constituents and to produce a cor- 195 responding amount of free carbon in the product.

200 In addition to producing pitches having different properties and characteristics, the present invention permits the production of distillates from tar or tar fractions or oils. Consequently it can be employed to distill a 205 dirty oil or an oil contaminated with tar or 210 pitch to produce a cleaner distillate oil there- 215 from and a pitch residue. In systems where 220 separate collector mains are employed each 225 collector main may be supplied with a differ- 230 ent material, for example, one may distill 235 tar in the manner described and another may 240 distill a mixture of oils for the separation of 245 the different oil constituents therefrom.

250 The gases escaping from the separate col- 255 lector main operated in the manner hereinbe- 260 fore described contain considerable quanti- 265 ties of vapors or oils derived from the dis- 270 tillation of the tar or oil therein. The gases, 275 being still at a relatively high temperature 280 in order that the oils may be retained in va- 285 por form and thus separated from the pitch, 290 may be subjected to any subsequent desirable 295 treatment for the purpose of effecting the 300 separation of the oil in fractions. Thus, the 305 gases may be conveyed through a series of 310 fractional condensers, each adapted to reduce 315 the temperature of the gases to a definite 320 point at which a desired fraction of the oil 325 will condense and separate and can be with- 330 drawn as a product of the operation. By 335 providing a suitable number of condensers 340 operated under regulated conditions to ac- 345 complish the desired purpose it is possible to 350 obtain the oil in fractions having definite 355 characteristics and qualities to meet the con- 360 ditions imposed by the market for such oils.

365 The apparatus of the present invention is 370 adapted for the distillation of tar and oils 375 generally and the recovery of distillates by 380 the utilization of the hot coke-oven gases by 385

bringing the tar or oil into direct contact therewith. The invention will be further illustrated by the following more detailed description which should be read with the accompanying drawings showing apparatus embodying the invention, but it is intended and will be understood that the invention is not limited to specific details of the apparatus as illustrated in the drawings, in which

10 Fig. 1 is a plan view of a coke oven illustrating one application of the invention thereto;

Fig. 2 is an end elevation, partially in section, of the structure illustrated in Fig. 1;

15 Fig. 3 is an enlarged sectional view of the short collector main; and

Fig. 4 is a view similar to Fig. 3 illustrating agitating means in the collector main.

Referring to Figs. 1 and 2 of the drawings, 20 5 indicates a battery of coke ovens having individual uptake pipes and goose-necks 6 which connect the ovens with a collector main 7. The latter may be of any usual form and construction and is designed to receive all 25 of the gases from the individual coke ovens and to deliver them through a centre box 8 to a cross-over main 9 which is connected to the condensing apparatus which may include the usual condensers 10. The gases 30 remaining after condensation may be delivered to an exhauster 11 and thence to the usual equipment provided for the further purification of the gases.

The goose-necks and collector main may be 35 equipped with the usual spray nozzles to permit the introduction of ammonia liquor, or ammonia liquor and tar, for the purpose of cooling the gases and flushing the tar which is thrown down in the collector main therefrom. The tar and ammonia liquor pass 40 from the centre box to the cross-over main and may be withdrawn and delivered to a decanter 13 in which the ammonia liquor is separated from the tar and utilized as desired. The tar from the decanter may be 45 accumulated in a tank 14 and delivered therefrom to the distilling apparatus as herein-after described.

The tarry oils which separate in the 50 condensers may be delivered to a decanter 15 and separated therein from ammonia liquor which can be utilized as desired. The oils may be added to the tar in the tank 14 or be treated separately. The apparatus as hereinbefore described includes the equipment 55 provided usually in coke-oven plants and it is designed to be operated in the usual manner to separate tar and oils from the coke-oven gases.

60 According to one adaptation of the present invention the coke oven will be provided with a separate collector main 16 which may be disposed at any convenient place contiguous to the ovens but is preferably supported 65 above and at the rear thereof and is con-

nected to a number of the ovens by separate uptake pipes and goose-necks 17. Suitable valves will be provided in the uptake pipes to permit direction of the gases from the selected ovens into the large collector main or 70 into the short collector main as desired. When the latter is used for distillation the gases from these ovens will be diverted from the large collector main into which they will otherwise flow. The goose-necks 17 and separate collector main 16 are provided with spray nozzles 18 to permit the introduction of tar or oil as a spray to the separate collector main so that the tar or oil will be mingled intimately with the hot coke-oven 80 gases flowing therethrough. The tar may be delivered to the sprays from the tank 14 through a pipe 19 by a pump 20. Tar may be supplied also through the pipe 19 and a branch pipe 21 to the end of the separate collector main for the purpose of maintaining a sufficient quantity of tar in the collector main to ensure proper flushing of the pitch therefrom. To permit recirculation of the pitch in the collector main an outlet pipe 22 may be connected to a pump 23 which can deliver the pitch to the main through a pipe 24. By manipulating the valves a portion of the pitch can be sent through the pipe 21' to the sprays. All or a portion of the pitch can thus be recirculated as desired and that portion which is not recirculated can be withdrawn through a pipe 25 and delivered to a tank 26.

Referring to Fig. 4 of the drawings, the 100 separate collector main may be provided, as a substitute for or auxiliary to the spray nozzles as hereinbefore described, with agitating means. Such means may comprise a shaft 30 extending through the collector main 105 and carrying a number of paddles 31 thereon. By the application of power from any suitable source the shaft may be rotated at a sufficient speed to ensure the thorough agitation of the tar or pitch in the collector main 110 and the throwing of particles of the tar or pitch into the stream of coke-oven gases passing therethrough. Such agitation will effect the desired intimate contact between the tar or pitch and the coke-oven gases and consequently will permit effective distillation of the tar or pitch and the production of vapor consisting of the vaporizable oils which can be condensed subsequently in the manner hereinafter described.

115 The distillation of the tar or oil in the separate collector main results in the enrichment of the normal gases by the volatile constituents of the tar or oil. These gases are withdrawn through a cross-over main 27 in which 120 a series of fractional condensers 28 may be disposed for the purpose of progressively cooling the gases and vapors to temperatures at which the desired fractions of the oil will 125 condense and separate so that these fractions 130

can be withdrawn as separate products. The gases which remain after condensation in the fractional condensers may be delivered through a pipe 29 to the exhauster 11 and thus mingled with the other gases produced by the coke-oven battery after separation of the tar and oils from these gases.

The arrangement as described permits the operation of the coke oven in the usual manner and the utilization of a portion of the heat in the hot coke-oven gases for the purpose of distilling tar derived from the gases issuing from the other ovens of the battery or tar from other sources. The apparatus as described, including a separate collector main or mains, is particularly useful where the quantity of tar to be distilled is relatively limited and insufficient to permit the distillation operation to be conducted with all of the gases from the battery or even those delivered normally to one collector main. It can be utilized, therefore, at isolated coke-oven plants where a single battery of coke ovens is operated and where the quantity of tar obtainable from other sources is relatively limited. It permits the production of pitch having the desired characteristics and the recovery of valuable oils from the tar in a simple, effective and economical manner.

The advantages of the invention have been set forth in some detail and the preferred embodiments have been described. It is to be understood, however, that various changes may be made in the form and arrangement of the apparatus without departing from the invention or sacrificing the advantages enumerated or any other advantageous results which may be accomplished by the application of the principles set forth.

I claim:—

1. An improved by-product recovery system for coal distillation plants having a considerable number of coal distillation ovens, comprising at least one collector main and condensing system for collecting the gases from a greater part of the ovens and for cooling the same to separate tar therefrom, at least one still each connected to a plurality of ovens comprising a small proportion of the ovens and adapted for the passage of the hot coal distillation gases therethrough, means for bringing the tar so separated into intimate contact with such gases while at a high temperature and for effecting intimate contact of the tar with the gases whereby rapid distillation of the tar can be effected, condensing means for condensing the distillate oils from the gases employed for such distillation, and means for mixing the gases after such condensation with the gases from the collector mains and condensers first mentioned so that the total admixed gases can be further purified by the same purifying operation.
2. In combination with ovens of a coke oven

battery a collector main, a condenser, means for passing gases from a large number of said ovens to the collector main, means for passing gases from the collector main to the condenser, a still, a second condenser, means for passing gases directly from a small plurality of the said large number of ovens to the still, means for passing vapors from the still to the second condenser and means for mixing gases from the first-mentioned condenser with gases from the second condenser so that both gases can be further purified by the same purifying operation.

3. In combination with ovens of a coke oven battery, a collector main, a condenser, means for passing gases from the collector main to the condenser, a still, means for introducing tar to the still, means within the still for bringing tar into intimate contact with gases therein, means for withdrawing pitch from the still, a second condenser, means for passing vapors from the still to the second condenser, an uptake pipe at one end of each of a large number of said ovens connecting these ovens with the collector main, means communicably connected with the opposite parts of each of a small plurality of said large number of ovens for passing gases directly from this small plurality of ovens to the still and means for mixing the gases from the first-mentioned condenser with the gases from the second condenser so that the total admixed gases can be further purified by the same purifying operation.

In testimony whereof I affix my signature. 100
STUART PARMELEE MILLER.
